PRINTER'S LOCKUP DEVICE

Henry J. Hilland, Chicago, Ill.

Application March 1, 1951, Serial No. 213,435

13 Claims. (Cl. 101—393)

1

The present invention relates to a printing type lock-up structure.

More particularly, the invention relates to a printing type lock-up structure of the variety utilizing two transversely disposed, relatively movable sets of parallel locking bars.

Known methods of setting printing type have heretofore required the use of what is known as a "printer's chase" which is nothing more than a rectangular frame that has fixed dimensions depending on the size printing press with which it is used, and that is designed to have the printing type to be formed mounted within it. With printing forms which are substantially equal in dimensions to the area enclosed by the chase, little trouble is experienced in mounting the type within the chase. However, with printing forms having dimensions which are smaller than the area enclosed by the chase, it is necessary to utilize varying numbers of different sized blocks, called "printer's furniture," with the printing form in order to support the form within the chase. Since considerable time and labor are required in order to support the printing form within the chase by means of the furniture, and since the furniture itself is relatively expensive, it is apparent that this method of locking up printing type securely is extremely costly and wasteful. In order to do away with the need for furniture when locking up printing type, a printing type lock-up structure was disclosed in my United States Letters Patent 1,525,937, issued February 10, 1925, in which two transversely disposed, relatively movable sets of parallel locking bars are used to retain a printing form within a chase in place of the furniture. While this form of lock-up structure is satisfactory in many respects, some difficulty has been experienced because of the manner in which the transversely disposed lock bars are secured together at their intersection.

It is therefore one object of the present invention to provide a novel printing type lock-up structure of the kind utilizing two relatively movable, transversely disposed pairs of parallel locking bars that can be used to lock up printing forms with or without substantial amounts of "printer's furniture," or quoins, and that greatly facilitates the locking up of printing forms.

Another object of the invention is to provide a novel printing type lock-up structure of the movable, intersecting locking bars variety wherein the individual bars of the lock-up device may be immediately and positively locked in a set position

2

relative to each other after having been properly aligned.

Still another object of the invention is to provide a novel, relatively cheap printing type lock-up structure of the movable, intersecting locking bar variety which does not require the use of locking collars, or otherwise, at the intersection of the individual locking bars in order to maintain the locking bars in assembled relation, and therefore is capable of handling larger printing forms than would otherwise be the case if locking collars were required.

A further object of the invention is to provide a printing type lock-up structure of the movable, intersecting locking bar variety wherein stresses imparted to the locking bars by the locked up printing form is absorbed mainly by the locking bars themselves, which are interlocked through the agency of intermeshing teeth, and does not have to be absorbed by locking collars, or the like, that are subject to mechanical failure.

A still further object of the invention is to provide a novel printing type lock-up structure which may be used with or without a printer's chase, and which consequently allows much larger printing forms to be used on a particular printing press than would otherwise be the case if the lock-up device had to be mounted within a chase.

A still further object of the invention is to provide a lock-up structure which may be used to simplify the locking up of printing forms on an angle.

A still further object of the invention is to provide a lock-up structure of the movable, intersecting locking bar variety having a simple safety locking latch for maintaining the bars in assembled relation.

A still further object of the invention is to provide an interlocking bar structure that may be used as a page tie-up, in place of string, or other known means used to tie up a page of type.

Still a further object of the invention is to provide a novel interlocking structure adapted for use as a galley for receiving type having removable interlocking ends.

A still further object of the invention is to provide an interlocking structure comprising an improved means for locking up a foundry form of type.

A feature of the invention is the provision of a novel, interlocking bar structure, including a first set of spaced, parallel locking bars having undulations formed on corresponding sides thereof, and a second set of spaced, parallel locking bars transversely disposed with relation to the first set of

locking bars, and having complementary undulations formed along the surfaces thereof adapted to engage and interlock with the undulated surfaces of the first set of locking bars.

Another feature of the invention is the provision of a novel printing type lock-up device of the movable, intersecting locking bar variety which includes two extra beveled bars that allow the device to be mounted on a printing press without using a "printer's chase."

A further feature of the invention is the provision of a printing type lock-up structure of the movable, intersecting bar variety, the intersecting bars having complementary undulated engaging surfaces which can be designed to allow for locking the bars at an angle.

Other objects, features, and many of the attendant advantages of this invention will be appreciated readily as the same becomes understood by reference to the following detailed description when considered in connection with the accompanying drawing, wherein similar parts in each of the several figures are designated by the same reference numeral, and wherein:

Fig. 1 is a plan view of a printing form mounted within a lock-up structure constructed in accordance with the invention;

Fig. 2 is a top perspective view of a portion of one of the intersecting bars comprising a part of the printing type lock-up structure shown in Fig. 1;

Fig. 3 is a bottom perspective view of the construction of a second locking bar that comprises a part of the printing type lock-up structure shown in Fig. 1;

Fig. 4 is a fragmentary sectional view taken through plane 4-4 of Fig. 5, showing the manner in which the transversely disposed locking bars are interlocked at the intersections thereof;

Fig. 5 is a fragmentary elevational view, partly in section, of one of the intersections of the transversely disposed locking bars taken through plane 5-5 of Fig. 1;

Fig. 6 is a plan view of one of the intersections of the transversely disposed locking bars;

Fig. 7 is an elevational view, partly in cross section, of one of the intersections of the transversely disposed locking bars taken through plane 7-7 of Fig. 1;

Fig. 8 is a top perspective view of the end of one of the locking bars showing the manner in which an additional end bar may be provided so that the lock-up structure comprising the invention can be mounted on a printing press without the use of a printer's chase; and

Fig. 9 is a bottom perspective view of the additional end member provided for use with the lock-up structure.

In practicing the invention, a printer's lock-up structure is provided for use in locking up printing forms to be placed on a printing press. The lock-up structure includes a first set of spaced, parallel locking bars having undulations formed on corresponding sides thereof, and a second set of spaced, parallel locking bars transversely disposed with relation to the first-mentioned set of bars, and having undulations formed on corresponding sides thereof. The undulated sides of the second set of locking bars are adapted to engage the undulated sides of the first set of locking bars, with the undulations in the second set of bars complementally meshing with the undulations in the first set of bars to firmly interlock the sets of bars against relative axial movement. To prevent the bars from being separated

by forces acting transverse to the longitudinal axes thereof, safety locking means may be provided at the intersections. And in order that the lock-up structure be capable of locking up larger printing forms on any given size printing press, additional end members are provided for use with the lock-up structure, which allow the device to be locked up on a printing press without the use of a printer's chase.

Referring now to Fig. 1 of the drawings, a printing form comprising a body of set printing type is shown at 11. The printing form is locked up within a novel printing type lock-up structure which includes a first set of spaced, parallel, elongated locking bars 12, and a second set of spaced, parallel, elongated locking bars 13 transversely mounted with relation to the first set of locking bars. The two sets of transversely disposed locking bars together define a generally rectangular shaped area for receiving the printing form which may be varied to accommodate any desired size printing form. The printing form is locked up in this area by means of a pair of printer's quoins 14 adapted to be inserted between the edge of the printing form 11 and the locking bar adjacent the particular edge in question, and then expanded to firmly lock the printing form within the lock-up device. The lock-up device with the printing form 11 locked up therein may then be locked within a printer's chase 16 which comprises a generally rectangular frame having tapered edges 17 by means of which the chase is clamped on a printing press.

The first set of locking bars 12 are generally rectangular in cross section, and have undulations formed on corresponding sides thereof. As is best seen in Fig. 2, the undulations comprise a plurality of longitudinally extending, rectangular-shaped grooves 17a formed on the upper side of each of the bars, and a plurality of transversely running teeth 18 formed on each of the inner and outer sides of the bar bordering upon the side containing grooves 17a. For a purpose hereinafter explained, the transversely extending teeth on one of the sides, namely the outermost sides when the bars are set in parallel relation in the manner shown in Fig. 1, extend only midway the thickness of the bar, and are undercut on the inner end, as at 19, to form an overhanging lip.

The second set of locking bars 13 are also generally rectangular in cross section, and have a plurality of undulations formed in corresponding sides thereof. The undulations in the second set of locking bars 13 are adapted to mesh with the undulations on locking bars 12, and as is best shown in Fig. 3, comprise a series of aligned, separated, rectangularly shaped, pedestal-like teeth 21 formed on the lower sides of each of the bars 13. Each of the bars also has a longitudinally extending groove 22 formed in that side which is outermost when the bars are set in parallel relation.

In assembling the printing form 11 within the lock-up structure, one of the sets of locking bars 12 is first laid out with the side thereof having grooves 17a therein facing upwardly, and one of the sets of locking bars 13 is then set transversely to, preferably at right angles, the locking bar 12 with the face thereof having teeth 21 thereon facing downwardly. To facilitate the setting of the locking bar 13 on the laid out locking bar 12, each of the locking bars 12 have a printer's scale 23 formed thereon which is used in determining the position of the transverse

locking bar 13. For a particular size printing form, the first of the locking bars 13 is placed on the laid out locking bar 12 at a distance of one-half of the vertical dimension of the form measured from the zero point of the scale. The zero point is located midway the end of the bar with markings of the scale increasing in each direction from the zero point towards each of the ends of the bar. In order that the printing form be properly centered in the lock-up structure, the position of the locking bar 12 relative to the locking bar 13 may be determined by means of a similar printer's scale 24 formed on each of the locking bars 13. Having positioned the locking bars in proper relation to one another, they are then pressed together so that the undulations or teeth 21 formed on the locking bar 13 mesh with the undulations or grooves 17a and voids between transverse teeth 18, in the manner shown in Fig. 4, to securely interlock the locking bars 12 and 13 against relative axial movement of the two. The printing form 11 is then placed so that one of the corners thereof is complementally received by the intersection of the locking bars. Quoins 14 are placed adjacent the edges of printing form not engaged by the previously set locking bars, and each of the remaining locking bars 12 and 13 positioned adjacent each of the quoins in intersecting relation. Upon pressing the last two mentioned locking bars into interlocking engagement with the first two mentioned locking bars, and tightening the quoins 14, the printing form will be locked up in the novel lock-up structure in the manner shown in Fig. 1.

From the above description, it can be readily appreciated that the lock-up device can be used to lock a printing form on a printing press without requiring the use of substantial amounts of printer's furniture, and therefore greatly facilitates the locking up of printing type on a printing press. Because of the manner in which the locking bars of the lock-up structure are interlocked, the device may be readily adjusted to accommodate any desired size printing form without requiring the setting or adjustment of a plurality of locking collars, or similar mechanisms, requiring time-consuming manipulation. All that is required is that the bars be aligned in a desired position, and simply pressed together. Once the locking bars are in a set position, they are firmly interlocked against stresses tending to bring about relative axial movement therebetween. Stresses such as those, due to the quoins 14 which normally tend to separate the locking bars, are absorbed mainly by the undulations or teeth formed in the locking bars themselves, and not by a locking collar or mechanism which would be subject to mechanical failure. Thus the lock-up structure is much more durable than previous devices of the same nature. Additionally, because no bulky locking collar mechanism is needed at the intersection of the locking bars, the novel lock-up structure can be used to lock up larger printing forms than otherwise if a locking collar mechanism were required.

To prevent the interlocking bars from being separated by forces acting transversely to the longitudinal axes of the locking bars, safety locking means are provided at the intersections of the bars. As is best shown in Figs. 5 through 7, the safety locking means comprises a mechanism including a base portion 26 slidably seated in the grooves 22 formed in each of the locking bars 13, and a locking latch portion 27 having a

hooked end 28 co-operating with the lip 19 formed in the undercut portions of the transversely extending teeth 18 on the outer sides of each of the locking bars 12. Base portion 26 and locking latch portion 27 of the mechanism are secured together by an operating handle portion 29 comprising a stem 31 threadably secured in base portion 26, and a handle receiving post 32 formed integrally with stem 31 and adapted to receive an operating handle. The base portion 26 of the safety locking means, when the operating handle portion 29 is loosened, can be set in any desired position along the length of the locking bars 13. Upon the locking bars being interlocked in a particular position, the safety locking means is slid along the locking bar until it is in position adjacent the intersection of the bar 13 with the bar 12. The latching portion 27 is then swung under lip 19, and the operating handle portion 29 then turned so as to draw latch portion 27 up tightly against the side of locking bar 13. This serves to firmly anchor the locking means in position relative to the locking bars, and to maintain the locking bars in assembled relation against the action of forces acting transversely to the longitudinal axes of the locking bar. Because of the simplicity of the construction of the safety locking means, it can be appreciated that the construction of the lock-up device is not greatly complicated by its provision, but is greatly improved thereby due to the fact that in handling the lock-up structures having printed forms mounted therein, there need be no fear of the device coming apart due to forces that might easily separate the locking bars.

This greatly facilitates handling and storage of the structures after printing forms have been set therein.

Having set locking bars 12 and 13 in a desired position, mounted a printing form therein, and set the safety locking means at the intersection of the locking bars, the printing form is then ready to be locked or placed on a printing press. In the embodiment of the invention shown in Fig. 1 of the drawings, the lock-up structure is placed on the printing press by means of the printer's chase 16. To facilitate the placing of the lock-up structure in the printer's chase 16, movable means comprising end locking screws 33 are provided on the ends of each of the bars 12 and 13. The end locking screws 33 comprise bolts having nut-shaped heads adapted to fit against the sides of the chase 17 which can be gripped with a wrench, and threaded stems 34 threadably secured in the ends of each of the locking bars. When placing the lock-up structure within the chase 17, the end screws 33 can be set in any desired position so as to rigidly lock the lock-up structure within the chase. It should be noted, however, that practically no strain at all is imparted to the chase except that required to support the weight of the lock-up structure, the printing form, and the quoins 14. The stresses brought about by reason of the quoins 14 are all absorbed by the interlocking teeth of the lock-up structure, and need not be absorbed by locking collars, or other similar mechanism, which might be subject to failure under such stresses.

From Fig. 1 it is apparent that a considerable amount of space on any particular printing press is taken up by the chase 17 which might otherwise be used to accommodate larger sized printing forms if the chase were not needed. In order to utilize this space, and do away with the need for printer's chase, the invention provides a lock-

up structure that can be placed on a printing press with or without using a chase. In order to accomplish this, a pair of additional longitudinal bars 37, one of which is shown in Fig. 8, are locked on opposite sides of the lock-up structure which do not require the use of end bars. Each of the longitudinal bars 37 has a tapered portion 38 similar to the tapered portion of the chase 17, and an overhanging edge portion 39 which has a series of spaced, pedestal-like, rectangular shaped teeth 41 formed on its under surface in the manner shown best in Fig. 9. The teeth 41 are, in all respects, similar to the teeth 21 on the locking bars 13, and serve the same purpose in that they mesh with the undulations in locking bars 12 to firmly interlock the additional longitudinal bars 37 with the ends of the locking bars 12 in substantially the same manner as is shown in Fig. 4 of the drawings. The overhanging edge portion of the additional end bars 37 also has a longitudinally extending groove 41a formed therein in which the base portion 26 of a safety locking means, identical in construction to the safety locking means illustrated in Figs. 5 through 7, is mounted. Upon the additional end bars being secured to the lock-up structure, the structure may be locked on a printing press without the use of a printer's chase, thereby allowing the space otherwise taken up by the chase to be used to accommodate a larger printing form 11.

While the invention has been described in connection with a printing type lock-up structure, it is contemplated that the invention be used in locking up foundry forms, in which the locking structure, or to be exact the portion of the locking structure surrounding the printing form would be so designed as to extend a height level with the height of the type. Further, the novel lock-up structure may be used as a page tie-up device in place of string or other presently used means for tying-up pages of type or printing forms after they have been made up, and before they are to be placed on a press. Consequently, the storage and handling of made up pages of type and printing forms is greatly facilitated by the invention.

A further intended use of the novel lock-up structure is in connection with the making-up of printing forms wherein the structure may be adapted for use as a "galley" having removable, reversible ends. By reversing the ends of a galley, thus constructed, the handling of type as it comes off the type setting machine is greatly facilitated. Also while the disclosed form of the undulations in the locking bars is particularly advantageous, it is to be understood that the invention is not to be restricted to the exact design disclosed but that the undulations may be shaped in any desired manner, the only requirement being that they cooperate to firmly interlock the locking bars of the locking device against relative axial movement. If desired, the teeth may be formed at some angle other than right angles so that the device can be used to mount printing forms set at an angle.

From the foregoing description it can be appreciated that the invention provides a novel printing type lock-up structure which facilitates the locking up of printing type forms on a printing press in that it does not require the use of printer's furniture, or other spacing-out devices such as the cross bars used on cylinder chases. The lock-up structure can be easily adjusted and aligned to accommodate any desired size printing form with a minimum of effort, and without re-

quiring time consuming adjustment of a complicated locking collar, or the like. Because of the manner in which the component parts therefor interlock, the possibility of mechanical failure of the structure is reduced to a minimum and the structure is capable of accommodating larger printing forms. The device can be easily adapted to accommodate even larger sized printing forms than could otherwise be used on a particular size press by the simple provision of a pair of additional longitudinal bars, and can be easily designed to provide for the mounting of printing forms on an angle. Thus, the invention provides a novel printing type lock-up structure incorporating many desirable features.

Having thus described my invention, it is obvious that various immaterial modifications may be made in the same without departing from the spirit of my invention; hence, I do not wish to be understood as limiting myself to the exact form, construction, arrangement, and combination of parts herein shown and described, or uses mentioned.

What I claim as new and desire to secure by Letters Patent is:

1. A lock-up structure including in combination a first set of spaced parallel locking bars having teeth and parallel rectangular shaped grooves transverse to the teeth formed on corresponding sides thereof, and a second set of spaced parallel locking bars transversely disposed with relation to said first-mentioned set of bars and having a series of aligned, separated, rectangular shaped pedestal-like teeth formed on corresponding sides thereof, the toothed sides of said second set of locking bars engaging the toothed and grooved sides of said first set of locking bars with the teeth in said second set of bars meshing with the teeth and grooves in said first set of bars to firmly interlock said sets of locking bars.

2. A lock-up structure including in combination a first set of spaced parallel elongated locking bars, said bars having a plurality of longitudinally extending grooves formed on corresponding sides thereof with each of said bars having transversely running teeth formed on each of the sides thereof bordering said grooved side, and a second set of spaced parallel elongated locking bars comprising a series of a plurality of separated pedestal-like teeth extending downwardly and formed on corresponding sides thereof, said second set of parallel locking bars being transversely disposed with relation to said first set of locking bars with the toothed sides of said second set of bars engaging the grooved side of said first set of bars, and the teeth of said second set of bars meshing with and partially filling in a complementary manner the voids in the grooved and toothed sides of said first set of bars to firmly interlock said sets of bars against relative axial movement.

3. A printer's lock-up structure including in combination a first set of spaced parallel elongated locking bars having a rectangular cross section, said locking bars also having a plurality of longitudinally extending rectangularly-shaped grooves formed on corresponding sides thereof with each of said bars having transversely running rectangularly-shaped teeth formed on each of the sides thereof bordering said grooved side, the teeth on one edge of said bars being undercut forming a lip extending the length of the bar, a second set of spaced parallel elongated locking bars having a series of a plurality of aligned, separated, pedestal-like, rectangularly-shaped

teeth extending downwardly and formed on corresponding sides thereof, said second set of parallel locking bars being transversely disposed with relation to said first set of locking bars with the toothed sides of said second set of bars engaging the grooved side of said first set of bars, and the teeth of said second set of bars meshing with and partially filling in a complementary manner the voids in the grooved and toothed sides of said first set of bars, and an additional set of end bars having portions adapted to be mounted on a printing press and portions having a plurality of aligned separated pedestal-like rectangularly-shaped teeth, said additional end bars having a groove formed in an edge thereof and being adapted to be transversely locked on the ends of said first set of bars with the toothed portions thereof interlocked with the grooves and teeth in said first set of locking bars, and said groove formed in an edge of the end bars adapted to receive a safety locking means complementally formed to the teeth and lip of the first set of locking bars, whereby said end bars and said first set of locking bars are adapted to be secured together at the intersection thereof to retain the same in assembled relation.

4. A lock-up structure including in combination a first set of spaced parallel elongated locking bars, said bars having a plurality of teeth formed on corresponding sides thereof, a second set of spaced parallel elongated locking bars having a plurality of teeth formed on corresponding sides thereof and a longitudinally extending groove formed in an edge of bars positioned above the teeth thereon, said second set of parallel locking bars being transversely disposed with relation to said first set of locking bars with the toothed sides of said second set of bars interlocked with the toothed sides of said first set of bars whereby relative axial movement of the two sets of bars is prevented, safety locking means complementally formed to the teeth of the first-mentioned locking bars and to the groove formed in the second set of locking bars and mounted at the intersection of said locking bars to prevent separation of the same, and movable means secured to the ends of said elongated locking bars to facilitate the mounting thereof in a printing press.

5. A lock-up structure including in combination a first set of spaced parallel elongated locking bars, said bars having a plurality of longitudinally extending grooves formed on corresponding sides thereof with each of said bars having transversely running teeth formed on each of the sides thereof bordering said grooved side, the outer sides of said bars having the transversely running teeth thereof extending midway the thickness of each of said bars with the inner end of said midway extending transverse teeth being undercut to form an overhanging lip, a second set of spaced parallel elongated locking bars having a series of aligned separated pedestal-like teeth formed on corresponding sides thereof, said second set of parallel locking bars being transversely disposed with relation to said first set of locking bars with the toothed sides of said second set of bars engaging the grooved side of said first set of bars, and the teeth of said second set of bars meshing with and partially filling in a complementary manner the voids in the grooved and toothed sides of said first set of bars to securely interlock said sets of bars against relative axial movement, each of said second set of locking bars also having a longitudinally running groove extending along the length of the toothed sides of said first set of bars to retain said bars in assembled relation.

outer sides thereof, safety locking means for preventing separation of said interlocked bars, said safety locking means including a base portion slidably seated in the groove in each of the outer sides of said second set of bars, a locking latch portion engageable with the lip formed on the inner end of the teeth on the outer side of said first set of bars, and an adjustable handle portion securing said latch portion to said base portion and adjustable to secure said safety locking means in a set position relative to said bars, said lock-up device also including additional end bars, each of said end bars having an over-hanging edge portion with separated pedestal-like teeth formed on the under surface of the overhanging portion, said additional end bars being adapted to be transversely disposed with respect to said first bars on the ends thereof with the teeth in the overhanging edge portion thereof partially filling in a complementary manner the voids in the grooved and toothed sides of said first set of bars to interlock said additional end bars and said first and second sets of bars against relative axial movement whereby said lock-up device may be locked on a printing press.

6. A printer's lock up structure including in combination a first set of spaced parallel elongated locking bars, said bars having a plurality of longitudinally extending grooves formed on corresponding sides thereof with each of said bars having transversely running teeth formed on each of the sides thereof bordering said grooved side, the outer sides of said bars having the transversely running teeth thereof extending midway the thickness of each of said bars with the inner end of said midway extending transverse teeth being undercut to form an overhanging lip, a second set of spaced parallel elongated locking bars having a series of aligned separated pedestal-like teeth formed on corresponding sides thereof, said second set of parallel locking bars being transversely disposed with relation to said first set of locking bars with the toothed sides of said second set of bars engaging the grooved side of said first set of bars, and the teeth of said second set of bars meshing with and partially filling in a complementary manner the voids in the grooved and toothed sides of said first set of bars to securely interlock said sets of bars against relative axial movement, and each of said second set of locking bars also having a longitudinally running groove extending along the length of the outer sides thereof, and safety locking means on the intersection of said bars for preventing separation of said interlocked bars, said safety locking means including a base portion slidably seated in the groove in each of the outer sides of said first set of bars, a locking latch portion engageable with the lip formed on the inner end of the teeth on the outer side of said first set of bars and an operating handle portion securing said latch portion to said base portion and movable to secure said safety means in a set position relative to said bars and to retain said bars in assembled relation.

7. A printer's lock-up structure including in combination a first set of spaced parallel elongated locking bars, said bars having a plurality of teeth formed on corresponding sides thereof with corresponding sides of said bars having additional indented portions, a second set of spaced parallel elongated locking bars having teeth formed on corresponding sides thereof, said second set of parallel locking bars being transversely disposed with relation to said first set of locking bars with

the toothed sides of said second set of bars engaging the toothed side of said first set of bars, and the teeth of said second set of bars meshing with and partially filling in a complementary manner the voids in the grooved and toothed sides of said first set of bars to firmly interlock said bars against relative axial movement, each of said second set of locking bars also having indented portions, safety locking means secured to said bars at the intersections thereof, said safety locking means including a base portion cooperating with the indented portion of one of said sets of bars, a latch portion cooperating with the indented portion of the other of said sets of bars, and an operating handle portion for securing said base and latch portions together and securing said safety locking means to said bars to prevent separation thereof, and means movably secured to the ends of each of said bars and expandable along the axes thereof for mounting said device within a chase.

8. A printer's lock-up structure including in combination a first set of spaced parallel elongated locking bars having a rectangular cross section and a plurality of longitudinally extending rectangularly-shaped grooves formed on corresponding sides thereof with each of said bars having transversely running rectangularly-shaped teeth formed on each of the sides thereof bordering said grooved side, the outer sides of said bars having the transversely running teeth thereof extending midway the thickness of each of said bars with the inner end of said midway extending transverse teeth being undercut to form an over-hanging lip, a printer's scale marked out along the longitudinal axis of the grooved sides of said bars, a second set of spaced parallel elongated locking bars having a rectangular cross section and a series of aligned separated pedestal-like teeth formed on corresponding sides thereof, and a printer's scale formed along the longitudinal axes thereof, said second set of parallel locking bars being transversely disposed with relation to said first set of locking bars with the toothed sides of said second set of bars engaging the grooved side of said first set of bars, and the teeth of said second set of bars meshing with and partially filling in a complementary manner the voids in the grooved and toothed sides of said first set of bars to securely interlock said sets of bars against relative axial movement, each of said second set of locking bars also having a longitudinally running groove extending along the length of the outer sides thereof, a plurality of safety locking means each secured on said bars at the intersections thereof and including a base portion slidably seated in the groove in each of the outer sides of said second set of bars, a locking latch portion engageable with the lip formed on the inner end of the teeth on the outer sides of said first set of bars and an adjustable handle portion securing said latch portion to said base portion and operative to secure said safety locking means in a set position relative to said bars, and axially movable end screws secured to ends of each of said bars to facilitate the mounting of said lock-up device on a printing press.

9. A lock-up structure including in combination a first set of spaced parallel locking members comprising laterally spaced parallel rectangular shaped grooves and transversely extending teeth formed on corresponding sides thereof and said grooves formed on the upper face and the teeth formed on the contiguous upper edges, and

a second set of spaced parallel locking members transversely disposed with relation to said first-mentioned set of members and comprising a series of aligned, separated, rectangular shaped pedestal-like teeth formed on corresponding sides thereof and extending downwardly, and the pedestal-like teeth of said second set of locking members complementary formed to and interlocked with the rectangular shaped grooves and transversely extending teeth of said first set of locking members.

10. A lock-up structure including at least one elongated member comprising laterally spaced parallel rectangular shaped grooves and transversely extending teeth, said grooves formed on the upper face and the teeth formed on the contiguous upper edges of said elongated member, and at least one other elongated member transversely disposed with relation to said first-mentioned elongated member and comprising a series of aligned, separated, rectangular shaped pedestal-like teeth extending downwardly, and a series of pedestal-like teeth of said last-mentioned member engaging the rectangular shaped grooves and transversely extending teeth of said first-mentioned member, and the series of pedestal-like teeth in said last-mentioned member being substantially complementary to and interlocked with the rectangular shaped grooves and transversely extending teeth in said first-mentioned member.

11. A printer's lock-up structure including at least one elongated bar comprising laterally spaced parallel rectangular shaped grooves and transversely extending teeth formed in one of the sides thereof and said grooves formed on the upper face and the teeth formed on the contiguous upper edges, the teeth on one of said edges being undercut forming a longitudinally extending lip, and at least one other elongated bar transversely disposed with relation to said first-mentioned elongated bar and comprising a series of aligned, separated, rectangular shaped pedestal-like teeth extending downwardly, the series of pedestal-like teeth of said last-mentioned bar engaging the rectangular shaped grooves and transversely extending teeth of said first-mentioned bar, and the series of pedestal-like teeth in said last-mentioned bar being substantially complementary to and interlocked with the grooves and transversely extending teeth in said first-mentioned bar, said second-mentioned bar having a longitudinally extending groove in an edge thereof, and safety locking means complementary formed to the longitudinally extending groove and to said teeth and said lip and secured to said bars at the intersection thereof to retain the same in assembled relation.

12. A printer's lock-up structure including in combination a first set of spaced parallel locking bars comprising laterally spaced parallel rectangular shaped grooves and transversely extending teeth formed in corresponding sides thereof and said grooves formed in the upper face and the teeth formed on the contiguous upper edges of each locking bar, a second set of spaced parallel locking bars transversely disposed with relation to said first-mentioned set of bars and comprising a series of aligned, separated, rectangular shaped pedestal-like teeth formed on corresponding sides thereof, the pedestal-like teeth of said second set of locking bars engaging the rectangular shaped grooves and transversely extending teeth of said first set of locking bars, and the pedestal-like teeth in said

13

second set of bars being complementary to and interlocked with the grooves and teeth in said first set of bars, and additional end bars having a series of downwardly extending pedestal-like teeth similarly formed to the first-mentioned pedestal-like teeth thereon, said pedestal-like teeth of said additional end bars being complementary to the grooves and teeth in at least one of said first-mentioned set of bars, and said additional end bars being adapted to be transversely mounted on the ends of at least one of said first-mentioned set of bars.

13. A safety locking means for a lock-up structure comprising intersecting locking bars, said safety locking means including a base portion and adapted to restrain intersecting locking bars in assembled relation at the intersection thereof, one of said locking bars formed with spaced parallel rectangular shaped grooves and transversely extending teeth on the upper edges of said bar, the teeth on one edge being rabbeted, the other of said locking bars formed with a series of aligned, separated, rectangular shaped pedestal-like teeth complementary to the grooves and

14

teeth formed on the first-mentioned bar, said second-mentioned bar along an edge thereof complementary formed to the base portion of the safety locking means, and said safety locking means complementary formed to the rabbeted edge and the teeth thereof of the first mentioned locking bar, and said safety locking means comprising operator operated means for adjustably securing said safety locking means and said locking bars together in the adjusted position of the locking bars.

HENRY J. HILLAND.
